ALFRED GERMAN ROSE, OF GAINSBOROUGH, ENGLAND, ASSIGNOR TO ROSE BROTHERS, GAINSBOROUGH, LIMITED, OF ALBION WORKS, GAINSBOROUGH, ENGLAND, A BRITISH COMPANY

MACHINE FOR WRAPPING CARAMELS OR LIKE ARTICLES

Application filed December 26, 1928, Serial No. 328,566, and in Great Britain January 4, 1928.

This invention is for improvements in or relating to wrapping machines for caramels or the like of the type comprising a movable carrier (such as a wheel, an endless chain, an oscillatable arm or the like) provided with one or more receiving pockets and movable intermittently to bring said pocket (or each pocket in turn as the case may be) into a position opposite to a reciprocating 10 pusher which operates intermittently to feed the caramels or other articles, one at a time, to the carrier. In this type of machine a wrapper (e. g. cut from a continuous web fed intermittently across the path of the pusher) is located in front of the receiving 15 pocket so that as the pusher advances the caramel the wrapper is carried with it and partially folded about the caramel, the completion of the folding operation being effected, in the case of a machine of the carrier 20 wheel type, during the continued step-by-step rotation of the wheel.

The present invention is concerned with a wrapping machine of the above type in which a continuous bar of confectionery stock is 25 fed towards the carrier, and a knife operates to sever successive portions in the length of the bar, and thereby form individual caramels or the like which are forced in turn by 30 the pusher into the carrier.

In machines of the carrier wheel type operating on a continuous bar of stock it has hitherto been customary (see for example, British specification No. 209,726) to feed the 35 leading end of the bar up to a position in front of the pusher and opposite to the periphery of the carrier wheel, and there to effect the cutting of the bar into separate caramels. With such an arrangement the 40 stock feeding rollers which guide the leading end of the bar into position are located immediately above the path of the pusher and close to the periphery of the carrier wheel, with the result that difficulty has been experienced in observing the progress of the 45 leading end of the bar and the formation of the separate caramels. Moreover, on account of the congestion of devices (stock feeding rollers, stock cutting knife, pusher, wrapper feeding rollers, wrapper cutting knife, and

associated parts) in the region of the wheel charging station, certain of said devices have necessarily been located in comparatively inaccessible positions. Difficulty has further been experienced in locating the wrapper 55 cutting knife sufficiently close to the carrier wheel to avoid the formation of undesirably long wrapper ends.

The above disadvantages are removed by this invention according to which the cutting 60 of separate caramels from the bar of stock is effected at a point spaced away from the path of the pusher, and transfer mechanism is provided to convey the caramels, one at a time, from the cutting station into the path of the 65 pusher.

Preferably, according to the invention the cutting station aforesaid is off-set laterally from the path of the pusher, and the transfer mechanism is arranged to convey the caramels through an arcuate path which meets the path of the pusher at an angle of approximately 90°. Stock-feeding mechanism (e. g. rollers) may be arranged to feed the stock up to the cutting station in a plane at right 70 angles to the plane of the carrier wheel and the aforesaid arcuate path may be a quadrant path struck from a centre which lies at the intersection of the aforesaid two planes.

In one construction according to the invention, the transfer mechanism comprises a channel-shaped holder (having a base and upstanding end walls) which is mounted to move in the arcuate path aforesaid and is arranged to engage the base and the front 80 and rear ends of the caramel. The caramel holder may be located between two quadrant guides arranged to form closures for the sides of the holder throughout its movement through the aforesaid arcuate path. Conveniently, there are several caramel holders 85 movable uni-directionally in sequence round a circle, whereof one quadrant forms the aforesaid arcuate path, so that each holder is in turn moved through that path. There 90 may be four holders mounted at equal angular intervals on a member which is rotatable step-by-step (e. g. by Geneva stop mechanism) so that while one holder is positioned 95 at the cutting station another is located in 100

register with the pusher, and at each step in the rotation of the member aforesaid a holder is moved from the cutting station into register with the pusher.

5 An example of the invention will now be described with reference to the accompanying drawings in which—

Figure 1 is a plan view showing the general arrangement of the machine.

10 Figure 2 is a front elevation of part of the machine, showing in particular the caramel feeding mechanism.

Figure 3 is a side view, partly in section, of the mechanism shown in Figure 2, and

15 Figure 4 is a plan of the rotary transfer member.

Like reference numerals indicate like parts throughout the drawings.

The machine is of the known type comprising 20 a carrier wheel 10 mounted for intermittent rotational movement about a horizontal axis. The carrier wheel is provided with peripheral caramel receiving pockets each constituted by a stationary jaw 11 (Figure 3) and a movable jaw 12. In the present example there are six pockets arranged at equally spaced intervals, and the carrier wheel is so driven as to move through one-sixth of a revolution at each step.

25 The stock which is in the form of a continuous bar 13 (Figure 2) is fed along a horizontal guideway 14 by means of feed rollers 15, 16 located one above the other, and thence over a bridge piece 17 and between rollers 18, 19 which are arranged side by side to feed the forward end of the bar downwardly through a vertical guide tube 20. The feed rollers 15, 16, 18 and 19 are all mounted with their axes at right-angles to that of the carrier wheel 10. Below the guide member 20 the bar is severed into separate caramels by a knife 21 which is operated to rotate continuously in a horizontal plane. The position to which the leading end of the stock bar is fed, and at which the knife operates, has hereinbefore been referred to as the cutting station, which (as will be seen from Figure 1) is off-set laterally from the plane of rotation of the carrier wheel 10. In order 30 to convey the caramels one at a time from the cutting station up to the carrier wheel the following mechanism is provided.

Referring to Figures 3 and 4, the transfer mechanism comprises a ring 22 carried on a sleeve 23 which is mounted for rotation on a fixed vertical pillar 24. The ring 22 has formed in it four channels 25 at equal intervals apart, and the ring has imparted to it a step-by-step rotational movement such that 35 at each step the ring is rotated through quarter of a revolution. The ring is driven through a Geneva stop mechanism comprising the usual star-wheel 26 and driving pin 27, such mechanism ensuring that between 40 each actuation of the ring the latter is held

securely against backward or forward movement.

The ring 22 is so positioned that during each of the intervals at which it is at rest, one of the channels 25 will be in a position immediately below the guide member 20, while an adjacent channel will be in a position (herein referred to as the wheel-charging station) opposite to the carrier wheel 10. Thus the arrangement is such that one quadrant of the circular path round which the channels 25 are moved, forms the quadrant path through which each caramel is conveyed from the cutting station to the wheel-charging station. The leading end of the bar of stock 13 is fed into one of the channels 25 and while in this position the knife 21 operates to sever the end portion of the bar thus forming an individual caramel. Each of the channels 25 forms a caramel holder to engage the base and opposite end walls of a caramel. During the movement of each channel 25 between the cutting station and the wheel-charging station, the sides of the channel are enclosed, on the outside of the ring by an arcuate guide 28, and on the inside of the ring by a circular head 59 carried on the fixed spindle 24 about the axis of which the ring rotates. The guides 28, 59 ensure that when the cutting of the bar of stock is effected the leading end (which will form the caramel) is enclosed on all four sides by the guides 28, 59 in conjunction with the end walls of the channel 25. This feature of the apparatus is important as the complete enclosure of the stock end during cutting prevents that distortion of the caramel which has been unavoidable in hitherto known machines.

Each caramel on arrival at the wheel-charging station is forced from the ring channel 25 into a receiving pocket of the carrier wheel by means of a pusher 29. The pusher is mounted on an arm 30 the outer end of which is hinged to a short link 31 attached to a sleeve 32 which in turn is mounted on a bracket 33 in such manner that the sleeve can turn about a vertical axis 34. The pusher is operated by a two-part lever 35, 36 pivotally mounted for rocking movement about a vertical axis 37. The part 36 of the lever is pivotally connected at its outer end (by a spindle 38) to a point intermediate in the length of the pusher arm 30 and the part 35 of the lever carries cam followers 39 co-operating with a cam (not shown) which imparts a to-and-fro movement to the lever and consequently a similar movement to the pusher arm. The various parts associated with the pusher are so arranged that the movement of the latter is confined substantially to a straight line path. The operative end of the pusher 29 is located within a groove 40 which extends diametrically across the circular head 59 and is opposite to the position occupied by each caramel-holder channel 25 when at the wheel-charging sta-

tion. During each forward stroke of the pusher, the leading end thereof engages a caramel at the charging station and forces it out of the channel 25 through a mouth-piece 41 and into one of the carrier wheel pockets.

Rollers 50 are arranged to feed a continuous wrapper strip 51 into a position between the periphery of the carrier wheel 10 and the mouth of the guide 41. In this position the leading end of the wrapper strip is held by two pairs of grippers 52, 53 and while so held is severed from the remainder of the strip by a knife 54, thus forming an individual wrapper for one caramel. The grippers 52, 53 are operated to open and close at the required times and to travel with the pusher 29 during its advance.

The machine operates in the following sequence. In the positions of the parts shown in Figure 1, the feed rollers 15-19 have been rotated to feed the end of the bar of stock into a caramel-holder 25 located below the guide tube 20. The end of the stock bar is now severed by the knife 21 and the caramel thus formed is conveyed to the wheel-charging station by partial rotation of the ring 22. By this time the leading end of the wrapper strip 51 has been fed to the front of the carrier wheel, a wrapper has been severed by the knife 54, and one of the pockets in the carrier wheel 10 is situated in the path of the pusher 29, the carrier wheel being stationary. The pusher is now advanced to force the caramel out of the channel 25 into the wheel pocket, the wrapper being wrapped, in known manner about the top and bottom surfaces of the caramel. During the continued step-by-step advance of the carrier wheel the wrapper is folded about the fourth side of the caramel so as to form an open-ended tube, the ends of which are closed by twisters 60 after the operation of which the wrapped caramel is discharged from the machine. While one of the caramel holders 25 is at the wheel charging station and while the pusher is operating, another holder is positioned at the cutting station and is receiving another caramel.

I claim:

1. In a wrapping machine of the type described operable on a continuous bar of confectionery stock, the combination of a movable carrier, a reciprocating pusher for feeding caramels one at a time to the carrier, stock feeding mechanism for feeding a bar of stock up to a cutting station which is located at a point offset laterally from the path of the charging pusher, a cutter for effecting wholly at the station aforesaid the entire operation of severing individual caramels from the bar, and transfer mechanism separate from the cutter to convey the caramels one at a time from the cutting station

through an arcuate path which is a quadrant of a circle into the path of the pusher.

2. In a wrapping machine of the type described operable on a continuous bar of confectionery stock, the combination of a rotatable carrier wheel having peripheral pockets, a reciprocating pusher for feeding caramels one at a time to the carrier, stock feeding mechanism for feeding the stock in a plane at right angles to the plane of the carrier wheel up to a cutting station which is located at a point offset laterally from the path of the charging pusher, a cutter for effecting wholly at the station aforesaid the entire operation of severing individual caramels from the bar, and transfer mechanism separate from the cutter to convey the caramels one at a time from the cutting station through an arcuate path which is a quadrant of a circle into the path of the pusher.

3. In a wrapping machine of the type described operable on a continuous bar of confectionery stock, the combination of a rotatable carrier wheel having peripheral pockets, a reciprocating pusher for feeding caramels one at a time to the carrier, stock feeding mechanism for feeding the stock in a plane at right angles to the plane of the carrier wheel up to a cutting station which is located at a point offset laterally from the path of the charging pusher, a cutter for effecting wholly at the station aforesaid the entire operation of severing individual caramels from the bar, and transfer mechanism, separate from the cutter, to convey caramels one at a time from the cutting station, through an arcuate path which is a quadrant of a circle struck from a center lying at the intersection of the planes aforesaid, into the path of the charging pusher.

4. In a wrapping machine of the type described operable on a continuous bar of confectionery stock, the combination of a rotatable carrier wheel having peripheral pockets, a reciprocating pusher for feeding caramels one at a time to the carrier, stock feeding mechanism for feeding the stock in a plane at right angles to the plane of the carrier wheel up to a cutting station which is located at a point offset laterally from the path of the charging pusher, a cutter for effecting wholly at the station aforesaid the entire operation of severing individual caramels from the bar, and transfer mechanism, separate from the cutter, to convey caramels one at a time from the cutting station, through an arcuate path which is a quadrant of a circle struck from a center lying at the intersection of the planes aforesaid, into the path of the charging pusher, the transfer mechanism comprising a caramel holder mounted to move in the quadrant path aforesaid.

5. In a wrapping machine of the type described operable on a continuous bar of con-

fectionery stock, the combination of a rotatable carrier wheel having peripheral pockets, a reciprocating pusher for feeding caramels one at a time to the carrier, stock feeding mechanism for feeding the stock in a plane at right angles to the plane of the carrier wheel up to a cutting station which is located at a point offset laterally from the path of the charging pusher, a cutter for effecting wholly at the station aforesaid the entire operation of severing individual caramels from the bar, and transfer mechanism, separate from the cutter, to convey caramels one at a time from the cutting station, through an arcuate path which is a quadrant of a circle from a center lying at the intersection of the planes aforesaid, into the path of the charging pusher, the transfer mechanism aforesaid comprising a plurality of caramel holders moving unidirectionally in sequence round a circle whereof one quadrant forms the aforesaid arcuate path, so that each holder is in turn moved through that path.

6. In a wrapping machine of the type described operable on a continuous bar of confectionery stock, the combination of a rotatable carrier wheel having peripheral pockets, a reciprocating pusher for feeding caramels one at a time to the carrier, transfer mechanism comprising a plurality of caramel holders embracing the front, rear and base of caramels, means to rotate said holders round a circular path to transport each caramel in turn through a quadrant of the circle from a cutting station, which is located at a point offset laterally from the path of the charging pusher, into said path, stationary quadrant guides arranged to form closures for the sides of the caramel holders during their movement through the quadrant, stock feeding mechanism for feeding the stock, into a caramel holder located at the cutting station, in a plane at right angles to the plane of the carrier wheel and to the plane of movement of the holder, and a cutter for effecting wholly at the station aforesaid the entire operation of severing individual caramels from the stock.

7. In a wrapping machine of the type described operable on a continuous bar of confectionery stock, the combination of a rotatable carrier wheel having peripheral pockets, a reciprocating pusher for feeding caramels one at a time to the carrier, transfer mechanism arranged to convey the caramels one a time from the cutting station, which is located at a point offset laterally from the path of the pusher, into the pusher path, said transfer mechanism comprising a member having four caramel holders mounted at equal angular intervals thereon, means to rotate said members step-by-step so that while one holder is at the cutting station another is in register with the pusher and at

each step in the rotation of the member aforesaid a holder is brought from the cutting station into register with the pusher, stationary quadrant guides arranged to form closures for the sides of the caramel holders during their movement from the cutting station into the path of the pusher, stock feeding mechanism for feeding the stock into a caramel holder which is located at the cutting station, in a plane at right angles to the plane of the carrier wheel and to the plane of movement of the holder, and a cutter for effecting wholly at the station aforesaid the entire operation of severing individual caramels from the stock.

8. The wrapping machine claimed in claim 7 combined with a Geneva stop mechanism for imparting the step-by-step rotational movement to the member on which the caramel holders aforesaid are mounted.

In testimony whereof I affix my signature.

ALFRED GERMAN ROSE.
